UNITED STATES PATENT OFFICE.

MARSHALL B. LLOYD, OF MENOMINEE, MICHIGAN, ASSIGNOR TO THE LLOYD MANUFACTURING CO., OF MENOMINEE, MICHIGAN, A CORPORATION OF MICHIGAN.

COLLAPSIBLE GO-CART.

1,124,152.

Specification of Letters Patent.

Patented Jan. 5, 1915.

Application filed February 12, 1910. Serial No. 543,611.

To all whom it may concern:

Be it known that I, MARSHALL B. LLOYD, a citizen of the United States, and resident of Menominee, county of Menominee, and State 5 of Michigan, have invented certain new and useful Improvements in Collapsible Go-Carts, of which the following is a full, true, clear, and exact description.

My invention relates to the foldable or 10 collapsible type of baby-carriage or go-cart.

The present application is directed to certain improvements in additions to and modifications of collapsible baby-carriage structures of the type claimed in my co-pending 15 application, Serial No. 543,610, filed February 12, 1910. The said co-pending application relates to a baby-carriage structure which may by a single movement be quickly and completely collapsed into a compact 20 parcel so that it may be easily carried about; and, which may also be opened by a single movement.

One of the features in my present invention resides in a novel foot-hood on the forward part of the main frame of the go-cart 25 and adapted to cover the feet and legs of the child. This hood may or may not be made collapsible and may be provided with means by which it may be readily connected to the body-frame in order that it may be collapsed or raised simultaneously with the collapse 30 on the opening of the rest of the carriage structure; and it may be adapted for ready disconnection to make it operable independently of the rest of the carriage structure.

Another feature consists of the provision 35 of ball and socket joints by which the braces extending between the cross-bars on the main frame and the supplemental wheel frames may be connected thereto. These ball and socket joints make possible a structure which operates smoothly and easily and at the same time maintain rigidity in said structure when the carriage is open for use.

Another feature resides in the means for 45 yieldingly suspending the body seat within the body proper thereby making riding easy and preventing the occupant from receiving the shocks incidental to the movement of the carriage over rough ground.

Another feature comprises a yoke extending 50 across the back of the carriage seat and pivotally connected with the body-frame, in

combination with yoke fastenings of novel form which serve to support the seat back 55 in different adjusted positions.

My invention also consists in novel frictional, pivotal connections between the canopy frame and the body-frame, each thereof comprising plates carried by said 60 frames and a friction spring washer all riveted together by a pivot pin or rivet and adapted to hold the canopy frame in any desired position without resort to manual fastenings. These plates may have their 65 surfaces beaded or crimped to increase the friction between them.

Still another feature consists in providing a supplemental framework for the wheels which will support the axles of said wheels 70 on both sides thereof, thereby preventing the axles of said wheels from bending out of their proper operating positions.

Still another feature comprises a locking yoke pivotally supported by the rear cross-bar and arranged by spring means to automatically engage a fixed rod in said main frame when the rear cross-bar is in that extreme position of its movement wherein the carriage is in condition to be used. This 80 lock is placed in a position where it is readily accessible to be operated by the foot. It is adapted to prevent the collapse of the carriage structure when the carriage is in condition for use.

Referring now to the accompanying drawings: Figure 1 is a view in elevation of a structure embodying my invention, the carriage being in condition for use; Fig. 2 is a rear end elevation of said carriage; Fig. 3 is a plan-view of the carriage looking in the direction of the arrow indicated in Fig. 2; Fig. 4 is a similar view showing the wheel-frames folded into parallel relation with the main frame; Fig. 5 is a view in elevation 95 showing the body and the foot-hood, together with the means for connecting said foot-hood with the body-framework; Fig. 6 is a detail view of the lock adapted to prevent the collapse of the carriage structure; Fig. 7 is a detail view of the frictional pivot connection between the canopy and the body frame work; Fig. 8 is a sectional view on line 8—8 of Fig. 7; Fig. 9 is a detail view of a modified form of the pivotal connection; 105 Fig. 10 is a sectional view on line 10—10 of

Fig. 9; Fig. 11 is a detail view of a modified form of seat back adjusting means; Fig. 12 is a detail sectional view of a modification showing a method of detachably securing the hood to the main frame; and Fig. 13 is a detail view of a ball and socket joint by which the braces are secured to the cross-bars and wheel frames.

Like parts are referred to by similar reference characters throughout the several views.

In that form of my invention which I have shown in the accompanying drawings, 1 represents a rectangularly-shaped main 15 frame which is adapted to support the collapsible superstructure and the inwardly folding supplemental wheel frames, both of these being movable relatively to said main frame and foldable into intimate relation thereto.

The superstructure I have indicated generally by 3 and the supplemental wheel frames by 2.

Referring now particularly to Figs. 1 and 2, the supplemental wheel frames comprise 25 parallel bars 4 arranged on both sides of the wheels 6, which are journaled therein. The ends of these bars are turned upwardly and terminate in the pivots 8 supported by the lugs 9 depending from the main frame 1. These frames, as seen by reference to Fig. 4, 30 are adapted to be swung on said pivots 8 toward each other into parallel relation with the main frame 1. The main frame is provided with a rear cross-bar 10 slidably 35 mounted to reciprocate to and fro on the guide rods 11, shown in Fig. 3. Between the wheel-frames, and substantially the center of said cross-bar, are provided diagonal brace rods, 12, serving to transmit the motion of the cross-bar 10 to the wheel-frames 2. These brace rods are connected to the cross-bar and wheel-frames by means of ball 40 and socket joints 13 which readily adapt themselves to the relative change in direction 45 of movement of said cross-bar and said wheel-frames. In the forward end of the frame is pivoted at 16 a cross-bar 15 depending below said main frame in a U shaped loop. The cross-bar also has extending be-

50 tween its substantial center and the wheel frames 2 a pair of brace rods 17. These brace rods are also connected to the said cross-bar and wheel frame by ball and socket joints, 18, adapted to operate in the same 55 manner as those of the rear brace-rods. It will be noted that both the rear and forward brace-rods 12 and 17, respectively, are intended to brace the wheel-frames against swinging on their pivots when the carriage 60 is open for use. The cross-bar 15 is provided with upward extensions 20 which serve as one of the ends of the body-frame or superstructure 3. The opposite ends of said structure 3 are formed by the bars 21 pivoted at 22 to the main frame 1. These sides

are connected by the links or arm-bars 23 pivotally connected thereto at points 24 and 25, respectively.

The superstructure really comprises two open frames, one on each side of the main frame, and are substantially parallelograms in form. The arm-bars 23, however, are made with their ends downwardly turned which raises practically the whole of said bars considerably above what they would be if they were straight. This offers the advantage that they produce a better appearance and provide a deeper and more comfortable body-frame.

The bars 21 have upward extensions which 80 are connected at their upper end by the bar 26' and are adapted to serve as a convenient operating handle for the carriage. The said bars 21 with their extensions 26 comprise a lever operating about the pivot 22 by which 85 the entire structure may be collapsed, and likewise opened by a single movement of the handle.

The handle 26, when swung on its pivot, 90 22, in the direction of the arrow, indicated in Fig. 1, transmits its motion through link 23 to cross-bar 15 by means of the extensions 20. The cross-bar rotates on its pivot 16 and causes the brace rods 17 to draw inwardly on the wheel-frames 2. Simultaneously with its movement, the cross-bar 10 is pushed forward along the main frame by means of the links 28 extending between, and pivotally connected at, the points 29 and 30 on the bars 21 and the cross-bar 10, 100 respectively. Likewise the braces 12 will operate to draw inwardly the wheel-frames 2. It will thus be seen that when the handle, 26, is swung on the pivot 22 its movement is transmitted throughout the entire carriage 105 and the body or superstructure will collapse and the wheel-frames will be drawn or folded inwardly simultaneously into parallel relation with the main frame and into a compact parcel which may be easily carried about.

Referring to Figs. 1, 3, 5 and 12, the hood 32 in its preferred form is provided with a collapsible or folding framework 33 pivoted at point 16 to the transverse pivot 115 rod 16'. This hood is arranged to collapse or fold downwardly parallel with the main frame. In order that it may be operated by the handle which collapses the rest of the carriage, connecting links 35 pivoted at one 120 end at points 36 36 to the frame of the hood are provided, the notches 37 in their other ends being adapted to engage lugs 38 carried by the extensions 20. It will be seen that these links may be hooked or unhooked 125 from the extensions 20 and that when they are hooked on to said lugs 38 they will receive the movement of the extensions 20 and transmit it to the frame of the foot-hood. It is clearly manifest then that by swinging 130

the operating handle 26 on the pivot 22 the entire carriage structure, including the foot-hood, may be folded into intimate relation to the main frame. The foot-hood, on the 5 other hand, may be folded or collapsed independently of the rest of the structure, if the links 35 are out of engagement with the extensions 20.

In order that the hood may be made 10 easily removable from the frame for repairs, I have shown in Fig. 12 a structure by which this can be accomplished. The pivot rod, 16' may be provided with threads and a nut 39 on one of its ends to permit it 15 to be removed from the frame 1. The forward end of the lower frame brace 33' of the hood frame 33 is provided with two fixed pins or projections 39' which, when the hood is in position, are inserted into two corresponding holes 39'' in the forward end of the 20 main frame 1. This forms a separable connection between the front end of the hood and the main frame 1, and prevents the front end of the hood from dropping down.

25 Thus it will be seen that in order to entirely remove the hood from the cart it is only necessary to remove the pivot rod 16 and then withdraw the pins 39' from said holes 39''.

30 Referring now to Fig. 6, I will describe the lock which is adapted to prevent the collapse of the carriage when it is in condition for use. Cross-bar 10 illustrated in cross-section in said Fig. 6 is provided with lugs 35 40 upon which are pivoted the arms 41. These arms are provided with downward projections 43 to which are secured the springs 42 adapted to maintain said arms normally in their lower positions. The arms 40 are also provided with notches which are intended to engage a rod 44 extending transversely of the main frame and fixed at a point in said main frame just beyond the extreme limit of rearward movement of the 45 cross-bar 10. Across the outer ends of said arms I have provided a yoke, 45, connecting the two arms rigidly so that they may be operated simultaneously. When it is desired to release the lock in order to collapse 50 the carriage, the yoke 45 is lifted thereby disengaging the notches from the rod 44. The handle 26 is then pressed forward and the cross-bar will move forward along its guides drawing with it the lock arms 41 55 which will slide along the upper side of the rod 44. During movement necessary to open the carriage the cross-bar 10 moves rearwardly carrying the lock-arms 41 with it. These arms slide rearwardly on the rod 44 until the notches therein register with said rod. When this happens the spring 42 will draw the arms 41 downwardly causing the notches to engage the rod 44 thus locking the carriage against closing.

60 Referring now to Figs. 7 and 8, 50 repre-

resents the converging ends of the canopy frame. These ends, 50, are secured to plates 52 on each side of the frame. Mounted on the arm bars 23 are other plates 53 similar in construction to the plates 52. These plates are adapted to be clamped together by the rivet 55. Between the face of each plate 52 and the head of the rivet, I have provided two spring washers 57 adapted to yieldingly press said plates into frictional engagement. The plates are correspondingly beaded at 56 in order to increase the friction between them. The friction between said plates should be sufficient so that when the canopy is adjusted on its pivot to 70 any position it will be automatically maintained in that position.

75 Fig. 10 shows a modified structure. In this modification I have left the surface of the plates smooth and have placed between 80 said plates the friction washers, 57.

85 In baby-carriages of this type it is desirable to be able to incline the back of the seat at any angle within reasonable limits. I have provided, therefore, convenient means 90 for maintaining the back of the seat in several adjusted positions. This may be seen in Fig. 5 wherein 60 represents the back of the seat pivoted at 61 to the seat proper. A rod 62 bent to U-shape and pivoted at its 95 ends to lugs 63 carried by the arm rods 23 is arranged to swing in the arc of a circle on said pivots and is intended to slide up and down along the rear surface of the back of the seat and to be guided thereon by 100 the guide-straps 64. This rod thereby provides a convenient means for holding the back of the seat in any adjusted position.

105 Fig. 11 shows a slight modification in the means for maintaining the back 60 in three predetermined positions. The back straps 65 at points intermediate their ends are doubled back on themselves to form a loop 66 into which the yoke 62 is adapted to enter. This forms a secure means of holding 110 the yoke in place in its intermediate position.

115 The body 70, which may be of any suitable material, is suspended by the side portions from the arm bars 23 of the superstructure. Extended across the lower edges of these side portions are the upwardly curved strap-springs 72, shown clearly in Fig. 2. The seat 73 is rested on these strap-springs and is secured thereto by any suitable means at a point substantially intermediate the ends of said springs. The seat is by this arrangement yieldingly suspended with relation to the rest of the carriage structure and the occupant of the car will 120 not be subjected to the shocks incident to the traveling of the carriage over rough ground since these shocks will be absorbed by such strap springs.

125 Secured at 80 by one of its ends to the 130

front edge of the seat 73 is an apron 81. The other end thereof is secured to the upper edge of a dashboard 82 fastened at its lower edge in the lower part of the foot-hood 32. Straps 83 extending from the dashboard through openings in the hood 32 are provided by which the apron 81 may be stretched tightly to produce a convenient foot-rest. The straps 83 may be detachably secured in any suitable manner to the frame or hood.

I do not specifically claim the hood structure as described herein, such being described and claimed in my co-pending divisional application filed April 13, 1912, Serial No. 690,464.

As many modifications of my invention will readily suggest themselves to one skilled in the art, I do not limit or confine my invention to the specific structures herein shown and described.

I claim:

1. In a collapsible baby-carriage the combination with a main frame, of inwardly folding supplemental wheel frames pivoted thereto, said supplemental frames comprising side bars the ends of which are turned upwardly and terminate in pivots, cross bars supported by said main frame, braces extending between said supplemental frames and said cross bars and connected thereto by ball and socket joints, and a handle for operating said cross bars to move said wheel frames inwardly and outwardly.

2. In a collapsible baby-carriage the combination with a main frame, of supplemental wheel frames pivotally hung from said main frame and adapted to fold inwardly, a slidably mounted cross bar and a pivotally mounted cross bar supported by said main frame, brace links connecting said cross bars and said wheel frames, a handle pivotally mounted on said main frame and linked to said cross bars for operating said wheel frames.

3. In a collapsible baby-carriage the combination with a main frame, a collapsible superstructure thereon, supplemental wheel frames pivoted beneath said main frame and foldable inwardly, a cross bar slidably mounted in said main frame linked to said superstructure and movable therewith, and links connecting said cross bar and said collapsible structure to said wheel frames to swing said wheel frames inwardly and outwardly.

4. In a collapsible baby carriage the combination with a main frame and a foldable handle member pivotally mounted at one end thereof, of supplemental wheel frames pivotally supported by said main frame to fold inwardly therebeneath, a cross bar linked to the handle member and mounted to reciprocate in said main frame and adapted to cause said wheel frames to fold in-

wardly, a U-shaped bar pivotally secured to said cross bar and movable therewith, a fixed rod carried by said main frame, and notches in said U-shaped bar adapted to engage said fixed rod when the cross bar is in one of its extreme positions to prevent movement of said cross bar.

5. In a collapsible baby carriage the combination with a main frame, of supplemental wheel frames pivotally mounted therebeneath and foldable into substantially parallel relation therewith, a handle member pivotally mounted upon one end of said main frame, a cross bar slidably mounted on said main frame and linked to said handle for movement therewith, links connecting said cross bar to said wheel frames whereby the forward and rearward movements of said handle swing said sub-frames inwardly and outwardly respectively.

6. In a collapsible baby-carriage the combination with a main frame and a handle member pivotally mounted upon the rear end thereof, of wheeled sub-frames pivotally mounted beneath said main frame and foldable into substantially parallel relation therewith, a cross bar in said main frame movably mounted thereon and linked to said handle member for movement therewith, cooperating means carried by said cross bar and said main frame for locking said cross bar at one limit of its movement, and links connecting said cross bar with said sub-frames whereby said sub-frames are moved inwardly and outwardly simultaneously with the forward and rearward movements respectively of said cross bar.

7. In a collapsible baby-carriage the combination with a main frame and a handle member pivotally mounted upon the rear end thereof, of a cross bar slidably mounted upon the main frame and linked to said handle member for movement therewith, a locking device adapted to retain the cross bar in its rearward position, said device being releasable by foot, wheeled sub-frames pivotally mounted beneath the main frame and foldable therebeneath when the carriage is collapsed, links connecting said cross bar with said wheeled frames for swinging said frames inwardly and outwardly as said cross bar is moved forwardly and rearwardly respectively.

8. In a collapsible baby-carriage the combination with a main frame and a handle member pivotally mounted at one end thereof, of a slidable cross bar mounted at the rear end of the main frame, links connecting said bar to said handle member for movement therewith, a pivoted cross bar mounted at the forward end of the main frame and linked to the handle member for movement therewith, wheeled sub-frames pivotally mounted beneath the main frame, and links connecting each of the cross bars to the sub-

frames for positively swinging said sub-frames inwardly and outwardly simultaneously with the movements of said handle member.

5 9. In a collapsible baby carriage the combination with a substantially rectangular main frame comprising side bars and end bars and a handle member pivotally mounted upon one end of said main frame, of 10 guide rods secured to the side bars of the main frame, a cross bar mounted to slide back and forth on said guide rods, links connecting said cross bar to said handle member for movement therewith, wheeled 15 sub-frames pivotally mounted beneath the main frame and links connecting said cross bar to said wheeled sub-frames for swinging said frames inwardly and outwardly simultaneously with the forward and rearward 20 movements respectively of said handle member.

10. In a collapsible baby-carriage a main frame and a handle member pivotally mounted thereon and movable into parallel 25 relation therewith to collapse the cart, a sub-frame pivotally mounted beneath each side of said main frame and operative connections between said sub-frames and said handle member for swinging said sub-frames 30 inwardly and outwardly simultaneously with the forward and rearward movements respectively of said handle member, each of said sub-frames comprising two parallel bars spaced apart and pivotally connected 35 at their ends to said main frame, and wheels pivotally mounted in said sub-frames between said parallel bars.

11. In a collapsible baby-carriage the combination with a normally horizontal 40 main frame and a handle member pivotally mounted on one end thereof and movable into substantially parallel relation thereto to collapse the cart, of sub-frames arranged to fold beneath the main frame and pivotally connected therewith, operative mechanism connecting said sub-frames with said handle member for swinging said sub-frames inwardly and outwardly, each of said sub-frames comprising substantially

horizontally extending parallel flat bars, 50 curved upwardly at their ends and pivotally joined to the main frame, and wheels interposed between said parallel bars and pivotally mounted thereon.

12. In a collapsible go-cart, a main frame, 55 depending members at the front and rear thereof, a wheel frame at each side of the main frame, each said wheel frame comprising a straight horizontal middle portion and up-turned end portions pivotally joined 60 to the depending portions of the main frame, a handle pivotally attached to the main frame, and wheel-frame actuating members comprising diagonal braces, connected by ball and socket joints, to the wheel 65 frames at the front and rear end and to movable members actuated from the handle.

13. In a collapsible go-cart, the combination of a main frame with fore and aft actuating members movably mounted thereon, a 70 handle and superstructure foldable on said main frame and operating said actuating members, wheeled sub-frames pivoted on opposite sides of the main frame and foldable beneath the same, pivotal links extending 75 diagonally from each said member to both sub-frames and the pivotal connections of said links comprising balls and sockets.

14. In a collapsible go-cart, the combination of a main frame with an actuating 80 member movably mounted thereon, a handle and superstructure foldable on said main frame and operating said actuating member, wheeled sub-frames pivoted on opposite sides of the main frame and foldable beneath the same, pivotal links extending 85 diagonally from the middle of said member to respective sub-frames, and the pivotal connections of said links comprising balls and sockets.

90 In testimony whereof, I have hereunto set my hand, this 29th day of January, 1910, in the presence of two subscribing witnesses.

MARSHALL B. LLOYD.
